UNITED STATES PATENT OFFICE.

GEORGE FISCHER, OF MERCER ISLAND, WASHINGTON.

WATER-MOTOR.

1,083,999.

Specification of Letters Patent. Patented Jan. 13, 1914.

Application filed March 18, 1913. Serial No. 755,157.

To all whom it may concern:

Be it known that I, GEORGE FISCHER, a citizen of the United States of America, and a resident of Mercer Island, in the county of King and State of Washington, have invented certain new and useful Improvements in Water-Motors, of which the following is a specification.

My invention has more particular reference to motors of that type wherein the prime mover consists of a float, and has for a primary object to provide a construction of this character which is simple, durable and capable of being readily set up in position for operation.

A further object resides in the provision of a novel construction wherein the initial upward movement of the float is augmented through pressure of the inflowing fluid.

Other objects will be set forth as my description progresses, and those features of construction, arrangements and combinations of parts on which I desire protection, succinctly defined in my annexed claims.

Referring to the accompanying drawing wherein like numerals of reference indicate like parts throughout: Figure 1 is a top-plan of my invention, portions of some of the parts being broken away. Fig. 2 is a vertical section thereof. Fig. 3 is a fragmentary vertical section through the supporting platform of the super-structure, and Fig. 4 is a fragmentary section through the lower portion of the chamber.

Referring to the drawing by numerals of reference, 1 indicates a casing having an internal chamber 2 whose lower end portion is bounded by a supplemental wall section 3. This supplemental wall section 3, which, as shown, is in the form of an annulus and bolted, as by bolts 5', to the bottom wall of casing 1, encircles an intake port 5, through which construction direct pressure of the fluid entering through port 5 will be applied to the float, as 6, to start the same on its travel. After this initial upward travel, float 6 passes from within the restricted lower portion of chamber 2 and will then continue to rise slowly and in a uniform manner through the buoyant force of the water.

Float 6 can be of any suitable construction but, in accordance with my invention and where wall section 3 is employed, it is of such diameter as to be received in said

wall section when lowered, at which time it will be suitably spaced from said wall section and form the bottom wall of casing 1, it conveniently resting on lugs, as 7, of wall section 3.

Reference numeral 8 indicates tracks having flanged upper and lower end portions seating on and being removably secured to supplemental wall section 3, as by screws 9. The inner faces of tracks 8 are formed with grooves in which vertically spaced guide members 10, fixed to float 6, slidably engage.

Reference numeral 11 indicates a platform removably secured, as by lag screws 12 to the flanged upper end portions of tracks 8.

Reference numeral 13 indicates spaced cross members of platform 11 on which are journaled shafts 14. These shafts are provided with loose pinions 15 having rigid arm extensions 16 equipped with pawls 17, which latter engage ratchet wheels 18 fixed to shafts 14, as shown more clearly in Fig. 3.

Pinions 15 are in mesh with racks 20, fixed to float 6, and through the provision of ratchet wheels 18 and their pawls 17, the said shafts 14 will be driven by their racks alternately in a common direction, one shaft operating during the rise of the float, and the other during lowering movement thereof.

In taking movement from shafts 14, I conveniently provide the latter with sprocket wheels over which a sprocket chain 21 takes. One of the shafts 14 is also provided with a pulley 22.

Reference numeral 24 indicates a pipe communicating with port 5, which pipe is provided with a suitable valve, as 25, having a stem 26 extending upwardly alongside casing 1 and provided on its upper end portion with a suitable operating handle 27.

My invention is shown as adapted to operate by the ebb and flow of water, casing 1 being mounted on suitable brackets 28 of piles 29. It can, however, be used where a rise and fall of water is artificially produced.

Having thus described my invention what I claim as new, and desire to secure by Letters Patent of the United States of America, is:

1. A casing provided with a chamber having its lower end portion reduced in diameter and provided with an inlet, a float adapted to be received in the lower end por-

tion of the chamber of said casing, and motion transmitting mechanism connected to said float.

2. A casing provided with a chamber having a fluid inlet in its lower portion, a hollow supplemental wall section for said chamber arranged in the lower portion thereof, a float in said chamber adapted for reception in said wall section when lowered, and motion transmitting mechanism connected to said float.

3. A casing provided with a chamber having a fluid inlet in its lower portion, a hollow supplemental wall section removably secured in the lower portion of said chamber.

ber, a float in said casing chamber, vertical tracks secured to said wall section, bearing members on said float engaged with said tracks, a platform on the upper end portions of said tracks, a rack secured to said float, and motion transmitting mechanism mounted on said platform and engaged with said rack.

Signed at Seattle, Washington, this 4th day of March 1913.

GEORGE FISCHER.
